UNITED STATES PATENT OFFICE.

JOHN R. DUNAVANT, OF JET, OKLAHOMA.

FILM-CLASP.

1,216,967.

Specification of Letters Patent. Patented Feb. 20, 1917.

Application filed December 13, 1916. Serial No. 136,806.

To all whom it may concern:

Be it known that I, JOHN R. DUNAVANT, a citizen of the United States, residing at Jet, in the county of Alfalfa and State of 5 Oklahoma, have invented new and useful Improvements in Film-Clasps, of which the following is a specification.

This invention relates to winding and reeling, and more particularly to web fasteners for attaching a web or a strip to the reel; and the object of the same is to produce an improved clasp for holding the inner end of a film on the core or hub of a film reel.

15 It is well known to operators of motion picture apparatus that when a delicate film is to be wound on a reel its end must be clasped to the core or hub thereof in such manner as to hold it reliably without tearing the film, and when the same is unwound from the reel means must be provided to disconnect the end from the hub with the same care. These objects are carried out by 20 my improved clasp which is operated entirely from the outside of the reel, and whose construction is more fully set forth 25 in the following specification and shown in the drawings, wherein:

Figure 1 is a front elevation of a reel 30 equipped with this invention.

Fig. 2 is a vertical section through the reel and clasp, showing the latter in full lines as closed and in dotted lines as open.

Fig. 3 is a perspective view of the clasp 35 with its several parts disconnected from each other.

In the drawings the heads or ends E of 40 the reel are shown as having spokes S and rims R, and the heads are connected by a central core or hub H as usual. When applying a film F to this reel, one end must be attached or clasped in some manner to the hub H, after which the entire reel is revolved in a proper direction to wind the 45 film around such hub and around its own convolutions thereon. The present invention contemplates the provision of an improved form of clasp for this purpose.

Coming now to the details of the invention 50 as well illustrated in the drawings, I form in one end F of the reel a hole or slot 1 extending across the base of one of the spokes S, and against the outer face of this end of the reel I lay a pintle 2 which is a 55 short piece of rod or heavy wire extending longitudinally of the slot and fastened at

its extremities to the reel end E by suitable means such as indicated at 3 in the drawings as loops struck up from the metal of which the reel end is composed. The hole 60 and therefore the pintle are so remote from the axis that they are just beyond the periphery of the hub H which is indicated by dotted lines in Fig. 1. So much of my invention as has been described forms one element. 65

As a second element I bend a rather stiff piece of wire into the shape shown at the right of Fig. 3. That is to say, starting from the point 4 I form the wire into a loop 70 5, then give it a sharp bend 6 at right angles to the length of the loop and continue it into a coil 7, then carry it upward and again downward to form a tongue 8. On the other side of the tongue I form a second 75 coil 9, and from the coil a straight stretch projects through the remote end of the loop 5 in an arm 10 whose free end, which is the other end of the wire, constitutes a handle 11. The two coils 7 and 9 are of a size to 80 loosely embrace the pintle 2 which acts as a pivot for this element, and when in place these coils stand within the slot 1, as seen in Fig. 1, and the loop 5 stands on the outside of the reel end E while the tongue 8 stands 85 inside the same and is of a length to lie across the hub H and clasp the film F thereto, as seen in Fig. 2.

The third element of this clasp is a spring 90 of fine, highly tempered wire, seen at the bottom of Fig. 3. The central portion is coiled into a helix as indicated at 12, from one end of which rises an arm 13 which lies against the outer face of the reel, and from the other end of the helix projects another 95 arm 14 which is intended to extend through the loop 5, the outer end of the arm 14 being formed into an eye 15 to surround one side bar of such loop to prevent the displacement of parts. The tension of this 100 spring normally throws the arm 10 outward and the tongue 8 upward off the hub H, but when the operator grasps the handle and raises it against the spoke S he puts the spring under tension and turns the two 105 coils on the pintle 2 so that the tongue 8 is turned down onto the hub H and clasps the film against the same. Finally I make a U-shaped incision into the spoke S immediately above this clasp, and bend out the 110 metal within such incision into a hook 20 under which the arm 10 may be engaged to

hold the clasp in working position. I have described this improved film clasp as applied to a reel when made, but it is obvious that it could be applied to an old reel 5 already in use by cutting the slot 1, forming the proper cuts at 3 and 20, and bending the parts to receive the element of the clasp itself as described above; or it might be possible to build this clasp on a sheet of 10 metal and cut the reel end E and insert such sheet. However, the manner of manufacturing this film clasp and applying it to the reel forms no part of the present invention and need not be described.

15 In use, an operator takes a reel provided with this clasp, disconnects the arm 10 from the hook 20, lays the end of the film F on the hub H, raises the arm and reengages it with the hook 20, and then turns the reel 20 to wind up the film as usual. On the other hand, when a film is unwound from a reel provided with this clasp and the inner end of the film is to be removed, it is only necessary to unhook the arm from the hooks 25 20 and release it, when the spring throws this clasp outward and raises the tongue 8 off the hub so that the film comes free of the latter without injuring the parts. The entire device is light and simple and occupies extremely little space, and I do not 30 wish to be limited to the materials or proportions of parts.

What is claimed as new is:

1. The combination with a reel comprising a hub, and two heads, one of which is provided with a slot transverse to its diameter and just outside the line of the hub, and a hook on this head and on the same diameter farther remote from the axis than 40 the slot; of a pintle secured to the outer face of the reel along the length of said slot, an element of L-shape having eyes at its angle revolvably mounted on said pintle, its inner arm constituting a tongue 45 adapted to lie on the hub when its outer arm lies against the reel head and may be engaged with said hook, and a spring throwing the tongue normally off the hub and the other arm of said element outward.
- 50 2. The combination with a reel comprising a hub, and two heads, one of which is provided with a slot transverse to its diameter and just outside the line of the hub; of a pintle secured to said head and overlying the slot, an L-shaped element pivot-

ally mounted at its angle on said pintle with its inner end constituting a tongue adapted to lie on the hub when its outer arm lies against the reel head, means for throwing the tongue normally off the hub, 60 and means for resisting said throwing means.

3. The combination with a film reel comprising a hub and two heads, one of which is provided with an opening outside the line 65 of the hub; of an L-shaped element pivoted at its angle in said opening, its inner arm constituting an arm adapted to lie on the hub and its outer arm constituting a handle, a spring throwing the tongue normally off the hub, and a hook on the reel head with which the arm may be manually engaged to hold the tongue against the hub.

4. The combination with a film reel comprising a hub and two heads, one of which is provided with an opening outside the line of the hub, and a pintle overlying said opening; of an L-shaped element having at its angle a pair of loops revolvably mounted on said pintle, its inner arm constituting a 75 tongue adapted to lie on the hub when its outer arm lies against the reel head, and a spring coiled on the pintle between said loops with one end engaging the reel and the other engaging the element for holding 80 the latter normally at one extreme of its movement.

5. The combination with a film reel comprising a hub and two heads, one of which has a slot transverse to its diameter outside 90 the line of the hub, loops struck up from said head at the extremities of the slot, and a pintle overlying the slot with its ends secured in said loops; of an element of stiff wire bent near one end into a transverse loop, extending thence into a coil, 95 thence into a tongue, thence into a second coil spaced from the first, and thence into an arm projecting through the loop and having a handle at its extremity, the coils being revolvably mounted on said pintle within said slot; and a spring coiled on the pintle between the coils with one end engaging the reel and the other engaging said loop to turn the element normally to one 100 extreme position, for the purpose set forth.

In testimony whereof I affix my signature.

JOHN R. DUNAVANT.
